UNITED STATES PATENT OFFICE.

EDWARD D. BENNETT, OF PULASKI, NEW YORK.

RAILROAD-TIE CONSTRUCTION.

No. 892,025.

Specification of Letters Patent.

Patented June 30, 1908.

Application filed September 10, 1906. Serial No. 333,893.

To all whom it may concern:

Be it known that I, EDWARD D. BENNETT, a citizen of the United States, residing at Pulaski, in the county of Oswego and State of New York, have invented certain new and useful Improvements in Railroad-Tie Construction, of which the following is a specification, reference being had therein to the accompanying drawing.

10 My invention relates to an improved railroad tie construction, and I declare that the following is a full, clear, concise and exact description thereof sufficient to enable one skilled in the art to make and use the same, 15 reference being had to the accompanying drawings in which like letters and numerals refer to like parts throughout.

Among the objects of the invention are to provide a rigid transverse support for the 20 rails; to provide means of some resiliency for supporting the rails and which can be readily replaced, and a structure which will reduce to a minimum the tendency of a rail-bed construction to creep or weave in any 25 direction and also prevent it from settling.

The construction comprises such a support which is to be embedded in the road-bed or set into the pavement of a street, the rails being immediately supported by blocks 30 which, projecting to or above the surface are accessible for repairs without disturbing the tie portion, and can be readily replaced since the cups which receive the rail-blocks are of a uniform size. The blocks being compara- 35 tively small can be specially treated with preservatives at comparatively small cost and can be made in quantities for immediate use and of superior material without any great cost.

40 In the drawings Figure 1 is a side view of the tie showing the rail-supporting members thereon on which are mounted the rails. Fig. 2 is an end view of the construction, and Fig. 3 is a cross-section view through one of 45 the rail-supporting blocks. Fig. 4 is a perspective view of a portion of the construction.

Referring to the figures more in detail, 1 represents a tie extending the width of the 50 rail construction adapted to support rails thereon. The tie is formed with horizontal portions 2 and the downwardly extending vertical portion 3. These are of such extent that the horizontally extending portions 55 cover a considerable surface of the ground or sub-structure on which the road is made,

giving the construction a maximum of support. The downward extension 3 is perhaps little less than the superficial width of the tie and is embedded in the sub-structure or road-bed, its extended surface preventing the tie from side movement. This tie being properly placed in the road-bed and the material of the bed being thoroughly tamped about it and under it there is a minimum of opportunity for the movement of the tie either in settling or in sliding, because the bed material when properly tamped forms an abutment under the horizontal extensions and against the vertical extension and any movement tends to solidify or harden such abutment since the form of the tie utilizes any such movement in compressing the material of such abutment. In paved streets the tie itself is intended to be embedded in the pavement, thus giving perfect support and it being unnecessary to disturb it in repairing the rail supports.

A further advantage over some constructions is that the tie can be replaced, the sub-structure being disturbed to the minimum degree, because the horizontally extended parts are at the surface, and the road-bed can be easily tamped under such part. In other constructions I am aware rails have 80 been made where there was a horizontal member, but this has been placed below the surface of the ground, rendering it more difficult to tamp under that surface and necessarily requiring that the sub-structure which 85 is above the horizontal portion be more or less loosened by traffic over the rails. It is obvious also that such a tie could not be replaced without disturbing the sub-structure, whereas in my form of tie all traffic move- 90 ment of the tie tends to press those parts of the sub-structure which support and hold the tie, while the arrangement is the simplest to permit thorough tamping and the tie 95 can be lifted out of place and a new one substituted without disturbing the sub-structure.

Below the horizontal portions of the rail and at each side of the vertical portion there are formed side walls 4, end walls 5 and bottom 6 integral with the tie, so formed as to provide a hollow box opening from the upper surface of the tie, as clearly indicated in Fig. 3. The bottom may be pierced, as at 7, to provide for drainage. In this box is placed 110 the rail-supporting member which may be of wood on account of its resiliency, and which

is shown by 8 and which I show as bolted through the bottom by bolts 9 and which has at its exposed portion the cross-bolts 10. On these blocks are placed the rails 11 by 5 spikes 12. The heads of the bolts 9 may be placed down so that the blocks can be removed without disturbing the bolts.

The boxes formed under the tie present ends 5 which prevent longitudinal movement of the tie. These surfaces are much greater than like surfaces on an ordinary tie, and, as above pointed out, the bed material being properly tamped forms between the two boxes an abutment which is capable of 15 being given great solidity so as to absolutely prevent any side movement of the track construction under the force of traffic which is especially likely to occur on curves. At the same time the rail-supports or blocks can be 20 of such material and size as to allow all necessary yield in the bed structure.

Having described my invention, what I claim as new and desire to secure by Letters Patent, is:

- 25 1. A metallic railroad tie comprising a flat horizontal member supported on the surface of the road-bed, and a flat vertical member integral therewith and on its medial line and extending below the same and into the road-bed, each being of uniform width throughout its length, the tie having boxes let into its upper surface of substantially the width of the horizontal member, the walls of each box forming cross-ribs transverse the tie and in 30 35 the angle between the said members and

forming supporting faces for the tie below the surface of the road-bed, each said box being adapted to contain a resilient rail-supporting member to support the rail slightly above the surface of the support of the tie, 40 and a block being secured in the box by means passing through the ties and independent of the said fastening means, substantially as shown.

2. A railway tie composed of two flat ribs 45 of equal length and each of uniform width throughout, the one being connected with the other on the medial longitudinal line thereof, the former resting on the surface of the road-bed and providing an extension surface for the support of the tie, and the latter having an extension surface projecting downwardly into the road-bed, the said tie being formed with boxes in it and below the face of the horizontal member, and a resilient 50 rail-supporting member seated in each of said boxes and extending substantially an equal distance below and above the surface of the tie, and having bolts passing therethrough along the side of the rail and bolts 55 passing vertically through the resilient member and through the bottom of the boxes, substantially as described.

In testimony whereof I affix my signature in presence of two witnesses.

EDWARD D. BENNETT.
